UNITED STATES PATENT OFFICE

ARTHUR McDougall DUCKHAM, OF LONDON, ENGLAND

TUNNEL KILN

Application filed July 16, 1928, Serial No. 293,083, and in Great Britain August 12, 1927.

This invention relates to recuperative annular muffle kilns of the kind in which the goods are moved through the kiln on a circular track and pass successively through a 5 preheating zone, a zone of open firing wherein they are fired by direct contact with hot combustion gases introduced into the interior of the kiln chamber, and a cooling zone, and wherein the hot combustion gases are 10 withdrawn from the zone of open firing into flues arranged in the walls of the preheating zone, where they serve to preheat indirectly the goods to be fired.

In known kilns of the character just referred to, the suction or pull of the chimney stack or fan acts only on the zone of open firing, the intention being that the atmosphere in the cooling and preheating zones shall be substantially quiescent. In practice, however, 20 convection currents are set up in the atmosphere in the cooler parts of the kiln in such a way that the atmosphere in the cooling zone moves along more or less circular paths in the direction away from the cooler parts 25 of the zone towards the firing zone. These convection currents not only dissipate heat from the hottest portion of the kiln, but also tend to interfere with the proper cooling of the goods leaving the kiln. The intensity of 30 such currents is enhanced by the presence of any air which may have filtered into the kiln. In my application for U. S. patent, Serial No. 182,148, filed April 8, 1927, I have described a kiln of the aforesaid character 35 wherein the portion of the kiln constituting the cooling zone is connected by a duct with the main waste gas flue for the purpose of minimizing convection currents apt to be set up in this zone.

40 The present invention improves the construction of the kiln in two respects, both connected with the rate of change of the temperature of the goods in their passage through the kiln.

45 On the cooling side of the zone of open heating, the formation of convection currents is minimized by connecting the exhaust duct or ducts with longitudinal flues in the walls of the kiln which flues are in communication 50 with the interior of the kiln at a part of the

cooling zone which is between the said duct or ducts and the zone of open heating.

The advantage of this construction is that the goods leaving the zone of open heating are more gradually cooled than they are when the longitudinal flues in the walls of the cooling zone of the kiln are used wholly for conveying secondary air for combustion, as in known constructions.

On the preheating side of the zone of open heating, the products of combustion that have left the said zone escape through ports at the lower part of the muffle chamber, and according to a further feature of the present invention, the ports are grouped and those of each group communicate with a separate duct in the lower part of the kiln wall, which duct in turn communicates under control with the waste gas flues in the walls of the kiln. In this manner the combustion products can be caused to pass among the goods to be preheated for as great a distance through the muffle as may be required with due regard to the nature of the goods and their sensitiveness to the detrimental effect of combustion gases.

55 The invention will be better understood by referring to the accompanying drawings, in which:—

Fig. 1 is a developed longitudinal section through the cooling zone, the zone of open heating and the preheating zone of an annular kiln.

Fig. 2 is a developed sectional plan.

Fig. 3 is a cross section on line 3—3 of Fig. 1 and

Fig. 4 is a cross section on line 4—4 of Fig. 1.

The travel of the goods is in the direction of the arrow in Fig. 2. Near the junction of the zone of open heating and the cooling zone 90 a number of vertically aligned ports *a* connect vertical flues *b* with the interior of the kiln, and horizontal flues *c* in the walls of the kiln connect the vertical flues *b* with like flues *d* towards the other end of the cooling zone. The last-named flues are connected by the exhaust ducts *e* with the main waste gas flue.

95 The remainder of the cooling zone has horizontal flues *f* in its walls for secondary air,

which, at the place where the flues *d* are situated is carried by ascending flues *g* into the horizontal flue *h* (Fig. 3) in the roof of the kiln and so to the combustion flues.

The result is that the first part of the cooling zone in the direction of travel is laterally protected from rapid radiation by a more or less quiescent or slow moving mass of combustion products in the lateral flues; a too rapid cooling of the goods is thus avoided; and the connection of the interior of the kiln chamber with the waste gas flue (by way of the ports *a*, flues *b*, *c* and *d*, and ducts *e*) has the effect of minimizing convection currents in the cooling zone.

In the preheating zone there are ducts *i* at the lower part of the walls and these ducts communicate with the interior of the kiln through the ports *k*. At the ports *k'* the ducts communicate with the flues *l* in the walls of the kiln, the communication being controlled by dampers *m*. It will be seen that if the dampers *m* of the first duct, namely, that next to the zone of open heating *n* be closed, the whole of the products of combustion will have to travel in the muffle chamber as far as the second duct and so on. *o* is the flue connecting flues *l* with the chimney stack.

Having thus described the nature of the said invention and the best means I know of carrying the same into practical effect, I claim:—

1. In an annular tunnel kiln of the kind herein referred to, longitudinal flues arranged in the walls of the cooling zone of the kiln, and an exhaust duct in communication with the said flues and with the waste gas flue, said flues having communication with the interior of the kiln chamber intermediate of the said duct and the zone of open firing.

2. In an annular tunnel kiln of the kind herein referred to, longitudinal flues arranged in the walls of the cooling zone, an exhaust duct in communication with said flues and with the waste gas flue, said flues communicating with the interior of the kiln chamber intermediately of the said duct and the zone of open firing, flues arranged in the walls of the preheating zone, and means for withdrawing combustion gases from the zone of open firing into the last-named flues, said means comprising a number of ports arranged in groups, and a duct for each group communicating with the ports of that group, and in controlled communication with the flues in the walls of the preheating zone.

3. In an annular tunnel kiln of the kind herein referred to, having flues arranged in the walls of the preheating zone, means for withdrawing combustion gas from the zone of open firing into said flues, said means comprising a number of ports arranged in groups and a duct for each group communicating

with the ports of that group and in controlled communication with the flues in the walls of the preheating zone.

In testimony whereof I have signed my name to this specification.

ARTHUR McDougall DUCKHAM.
